AUTOMATIC PHONOGRAPH

Emil C. Mueller, Chicago, Ill., assignor to The
John Gabel Manufacturing Company, Chicago,
Ill., a corporation of Illinois

Application November 9, 1931, Serial No. 573,738

19 Claims. (Cl. 274—10)

This invention relates to improvements in an automatic phonograph, i. e., a phonograph which embodies mechanism for playing phonograph records and mechanism for storing a plurality of records, together with means for automatically transferring a record from the magazine to the turntable and from the turntable to the magazine.

The main objects of the invention are: To provide an automatic phonograph of the type referred to, of simple but efficient construction; that is to say, a phonograph which is free from highly complicated mechanism which would be apt to get out of working order; to provide an automatic phonograph which is of compact construction so that it will fit into a comparatively small cabinet or casing, and, in general, it is the object of the invention to provide an improved automatic phonograph of the type referred to.

Other objects and advantages of the invention will be understood by reference to the following specification and accompanying drawings (six sheets), in which an automatic phonograph embodying a selected form of the invention is illustrated.

In the drawings:

Figure 1 is a plan.

Figure 2 is an end elevation of the left-hand end of Figure 1.

Figure 3 is a section on the line 3—3 of Figure 1.

Figure 4 is a section similar to Figure 3, but showing certain parts of the mechanism in a changed position.

Figure 5 is a section on the line 5—5 of Figure 3.

Figure 6 is a section on the line 6—6 of Figure 3.

Figure 7 is an illustration of a certain detail of construction.

Referring now to the drawings, my improved phonograph mechanism is mounted in a frame of generally rectangular portions. The frame includes a base frame 10 of cast metal or other suitable construction, as clearly shown in Figure 3, and suitable uprights, such as indicated at 11, which support top frame members, such as shown at 12, 12^a, 12^b and 12^c. The top frame member 12^c is a substantially square frame element, as clearly shown in Figure 1.

The phonograph playing mechanism includes a turntable 13 mounted on the upper end of a spindle 14, the spindle 14 having a bearing near its upper end in a longitudinally extending frame

element 15, as indicated at 16, and a bearing at its lower end, as indicated at 17, the lower bearing constituting a part of the lower or base frame 10. The spindle 14 is suitably supported against downward sliding movement at its lower end in the bearing 17, and it is adapted to be rotated by means of an electric motor 18 which is provided with a motor shaft 19 geared to the spindle 14 by means of gears 20 and 21 which are secured to the shafts 19 and 14, respectively. 10 Suitable coin-controlled mechanism, herein designated C, including an electric switch 22, may be provided for controlling an electric circuit to the motor 18 or an ordinary manually controlled electric switch may be provided if the 15 coin-control element is not desired. The arrangement is such that the motor 18, and thereby the turntable 13, is continuously driven during all operations of the mechanism which will presently be described. The coin-control mechanism may be of any suitable type, and inasmuch as no invention is claimed in the specific type of coin-control mechanism, no detail description thereof will be given in this application.

For co-operating with a record on the turntable 13, an electric pick-up 23 is provided, the pick-up having suitable means indicated at 24 for holding a needle or stylus 25. The pick-up 23 includes or is supported by a supporting arm 26 which is provided, as indicated at 27, for vertical swinging movement about a horizontal axis and, as indicated at 28, for horizontal swinging movement about a vertical axis. The horizontal pivot axis is formed by means of a horizontally extending pivot pin which extends 35 through an end portion 29 of the supporting arm 26 and a head portion 30 of the vertical pivot pin 31 which is journaled in a bearing 32 which depends from the top frame member 12^a. (See Figure 2.) The pick-up member 23 is secured 40 to the free end of the supporting arm 26 by means of an arm or bracket 33 which is rigidly secured at one end to the pick-up member 23 and pivoted, as indicated at 34, to the free end of the supporting arm 26. The bracket 33 extends 45 beyond the pivot 34 and has its free end provided with a depending pin 35 which fits in a slot 36 in the adjacent end of an arm or lever 37 which is pivoted intermediate its ends, as indicated at 38, to the supporting arm 26. The 50 other end of the lever 37 is slotted, as indicated at 39, and straddles a pin 40 which extends upwardly from, and is held in, fixed position by the top frame member 12^a. (See Figures 1 and 3.) The lever arrangement, just described, for 55

mounting the pick-up device 23 is such that the pick-up member 23 is maintained in substantially fixed, predetermined relation to a radius of the record in all positions of its travel across the face 5 of the record. The main purpose of this arrangement is to facilitate the use of so-called permanent needles or styluses which, in their present commercial form, embody a chisel-like point which must not be turned at an angle in the 10 sound groove of a record which it engages. The above-described arrangement is such that the pick-up device and the chisel-shaped needle end are maintained substantially tangent to the engaged record groove in all positions of the 15 pick-up device. By reference to Figure 1, it will be seen that when the pick-up device 23 starts to travel inwardly across the face of a record on the turntable 13, it will travel in an arc about the vertical pivot axis 28 of the supporting arm 26, and that the lever 37 will be caused to swing on its intermediate pivot 38 by reason of its engagement at one end with the fixed pin 40, the result being that the opposite 20 end of the lever 37 tends to swing the pick-up member 23 about the pivot 34 in a direction reverse to the direction of travel across the face 25 of the record.

When the playing of a record is completed, the pick-up device 23 is automatically elevated so 30 as to remove the stylus 25 from the record groove and it is thereupon returned to its initial or starting position, as illustrated in Figure 1. For accomplishing this, a spider 41 is provided, this spider being secured to the upper end of a rod or bar 42 which is mounted for vertical sliding movement in bearing openings such as indicated at 43 and 44 in the top frame member 12a and base frame member 10, respectively. The spider 41 includes a forwardly projecting arm portion 41a which carries a depending record-centering pin 45, and it includes a laterally extending arm 46 which extends under the pick-up supporting arm 26, as clearly shown in Figures 1 and 3. The outer or free end of the laterally extending arm 46 is provided with a downwardly extending pin 47 which is slidable in a suitable opening in an ear 48 constituting a part of the top frame member 12.

Vertical movement of the rod or bar 42 is effected by means of a cam 49 which is carried by a cam shaft 50, the latter being mounted for rotation in suitable bearings carried by upstanding base frame parts 51 and 52, as clearly shown in Figures 2 and 3. The cam 49 actuates the rod 42 through the agency of a lever 53 which is pivoted intermediate its ends, as indicated at 54, on a lug 55 extending upwardly from the base frame 10. One end 56 of the lever 53 engages the peripheral cam surface 49, while the other end 57 of the lever engages a cross pin 58 carried by the rod 42. It will be seen that when the cam 49 depresses the end 56 of the lever, that the end 57 will be swung upwardly, and that through its engagement with the pin 58 the rod 42 will 65 be elevated. When the rod is thus elevated, the centering pin 55 will be withdrawn from the record, as indicated in Figure 3, and the arm 46, engaging an ear 59 which depends from the arm 33 of the pick-up mechanism will elevate the 70 pick-up by swinging the same upwardly about the horizontal pivot 27.

As an incident to such elevation of the pick-up device, it is swung from its innermost position to its outer or starting position. The means for 75 effecting such return movement includes an arm

60 which is secured to the lower end of the pivot pin 31, and a bell crank 61, one arm 62 of which is connected by means of a link 63 to the arm 60. The connection between the link 63 and arm 60 is preferably an adjustable connection formed by providing the arm 60 with a tapped, apertured ear adapted to receive the screw-threaded end of the link, as clearly illustrated. The other arm 64 of the bell crank 61 extends into the path of a pin 65 which is carried by the rod 42. The bell 10 crank 61 is pivoted in a depending lug or ear portion 66 which depends from the top frame member 12a. It will be seen that when the bell crank 15 is rocked counter-clockwise (see Figure 2) by reason of the upward movement of the rod 42 and engagement of its pin 65 with the bell crank arm 64, the lever 60 will be swung counter-clockwise (in Figure 5) so that the supporting arm 20 26 and pick-up member 23 are correspondingly moved to outer or starting position. The laterally 25 extending arm 46 of the spider 41 is provided with a stop shoulder 67 and with a notch 68 for co-operating with the ear 59 to position the pick-up with its stylus immediately above the outer groove of a record placed on the turntable. 25

Upon downward movement of the rod 42 and parts carried thereby, it will be seen that the pick-up 30 23 will be gently lowered until its stylus engages the record. In the event that the first sound groove of the record is spaced inwardly 35 from the point at which the stylus engages the record, a spring 69 serves to initially swing the pick-up device inwardly until the sound groove is engaged. It will, of course, be understood that the spider 41 is lowered a sufficient distance after 35 the stylus engages the record to cause the ear 59 to leave the groove or notch 68 so that the pick-up may freely follow the sound grooves of the record and travel crosswise thereof.

The cam shaft 50 and the various cams thereon 40 are actuated automatically upon completion of the playing of a record. The mechanism for actuating the cam shaft will now be described.

For transmitting power to the cam shaft 50, the shaft is provided with a worm wheel 70 which 45 meshes with a worm gear 71 rotatably mounted on the spindle 14. The upper end of the worm gear 71 is provided with a clutch notch 72 (see Figures 3 and 4) adapted to receive a clutch lug 73 of a clutch element 74 which is slidably 50 mounted on the spindle 14. The clutch member 74, while slidably mounted, is held against rotation relative to the spindle by means of a pin 75 carried by the spindle and projecting into a notch 76 provided in the clutch member. The 55 clutch member 74 is adapted to gravitate into engagement with the clutch end of the worm gear 71 when permitted to do so. For controlling such sliding movement of the clutch member 74, a lever or arm 77 is provided, the arm 77 being pivoted at its outer end, as indicated at 78, to the vertically adjustable rod 42, and provided at its inner end with forked arms 79 which straddle the clutch member 74 and fit into an annular groove 80. 60

A fulcrum for the lever 77 intermediate its ends is provided by means of a depending hook member 81 which is pivoted at its upper end, as indicated at 82, to a lug 83 depending from the top frame member 15. The hook 81 is adapted 70 to swing transversely of the length of the lever 77 and near its lower end is recessed in one edge to provide a fulcrum seat 84 which is adapted to receive the bottom edge of the lever 77. The hook member 81 is connected by means of a link 75

85 to the lower end of the depending arm 86 of a bell crank lever which is pivoted, as indicated at 87, on a lug portion 88^a of the frame member 15. The other arm 88 of the bell crank lever extends substantially horizontally and is serrated on its top edge, as indicated at 89. A spring 90, extending between an ear 91 of the bell crank lever and a pin 92 carried by the lug element 88, serves to normally swing the bell crank lever 86—88 until the arm 86 engages a stop pin 93 which is carried by the said lug 88^a. The bell crank arm 86 is provided with a forwardly extending ear 94 which is adapted to be engaged by an adjustable screw 95 carried by the lower end of a depending 5 lug 96 formed integral with the arm 60.

During the playing of a record, the clutch member 74 is held disengaged from the clutch end of the worm gear 71 by means of the lever 77 which rests intermediate its ends on the fulcrum seat 84, the outer end of the lever being held in down position with the rod 42, it being understood that the latter is in down position when a record is being played. Disk records such as are played on the phonograph mechanism herein involved are ordinarily provided with an innermost groove, the diameter of which is approximately uniform for all records. If the actual sound groove terminates before the innermost groove is reached, a quick spiral groove is provided for conveying the 20 pick-up device from the actual sound groove to the innermost groove just referred to. The adjustable screw 95 is so adjusted that when the pick-up device travels over a quick spiral groove such as referred to, the screw will engage the 25 ear 94 and thereby swing the depending arm 86 about its pivot 87. Such swinging movement is transmitted through the link 85 to the hook lever 81 which is accordingly swung (to the right in Figure 2), with the result that the fulcrum seat 30 84 is removed from under the lever 77, thereby permitting the lever to swing downwardly about its pivot 78, with the result that the clutch member 74 engages the clutch end of the worm gear 71. Thereupon, the cam shaft 50 and cam 49 are 35 rotated, with the result that the lever 53 is actuated to elevate the rod 42 to accomplish the 40 functions previously explained.

The bell crank arm 88 with its serrated top edge 45 89 is provided for co-operating with a dog 97 which is pivoted at 98 in the free end of the arm 60 (see Figures 2 and 5). When the pick-up device 23 travels over the face of a record the dog 97 rides over the serrated top edge of the bell 50 crank arm 88, necessarily assuming a position at an angle to the vertical, the angle being approximately 45 degrees. It will be observed that if it is desired to stop the playing of a record, it is only necessary to manually lift the pick-up device and supporting arm 26 and to swing the same 55 towards its starting position, the result being that the dog 97 will force the bell crank arm 88 downwardly, thereby swinging the bell crank arm 86 to the right to effect the engagement of the clutch elements 14 and 71 and operation of the cam shaft 50, as previously described.

A record magazine associated with the playing mechanism previously described comprises a frame element 100 which is in the form of a rectangular loop. The frame loop 100 is vertically, slidably mounted on rods 101—101 at opposite sides of the frame by means of ears 102 which extend laterally from the opposite ends of the frame 100 and by means of ears 103—103 which extend laterally from the lower ends of 60 downwardly extending lugs 104. It will be under-

stood that the ears 102 and 103 are apertured to slidably fit the rods 101. Mounted within the looped frame 100 is a shelf structure embodying a plurality of vertically spaced shelves 105, each of which serves as a support for a record R.

The magazine structure just described is supported by means of a lever 106 which is pivoted intermediate its ends, as indicated at 107, and lug 108 which extends upwardly from the base frame. The rearward portion of the lever 10 106 is provided with an anti-friction roller 109 which engages the edge of a cam member 110 which is rotatably mounted on a shaft 111, the latter being rotatably supported in upwardly extending posts 112—112, as clearly shown in Figure 6. The front end of the arm 106 is provided with a depending portion 113, the lower end of 15 which is connected by means of a link 114 to a depending post 115 formed integral with the rectangular magazine frame 100. The lower end 20 of the link 114 is pivoted to the arm 113 by means of a suitable pivot screw, as indicated at 116, and the upper end of the link 114 is connected to the post 115 by having its upper end screw-threaded and fitting a correspondingly 25 tapped aperture in a pin 117 which is rotatably mounted in the post 115. It will be observed that the threaded connection between the link 114 and pin or stud 117 provides for adjustment 30 of the magazine relative to the lever 106. For counterbalancing the weight of the magazine and records carried thereby, the forward end of the lever 106 is connected by means of a spring 118 to a stationary portion 119 of the base frame. 35

It will be evident that the cam 110 is operative to control the position of the magazine 100. For automatically rotating the cam 110 step by step, the following mechanism is provided: A ratchet wheel 120 is rigidly secured to the cam 110 so as to be rotatable therewith and a pawl 121 is associated with the ratchet for moving the same. The free end of the pawl 121 is provided with a laterally extending portion 122 which is adapted to engage behind the respective teeth of the ratchet wheel, and the other 45 end of the pawl is pivoted to the upper end of a lever 123, the lower end of which is pivoted to the lug 119. Intermediate its ends, the lever 123 is provided with an ear 124 which pivotally receives one end of a link or thrust rod 125, the other end of which is pivotally connected to the upper end of a lever 126, the lower end of the latter being pivoted, as indicated at 127, to a lug projecting upwardly from the base frame 10. The lever 126 is also provided with an anti-friction roller 128 which engages the periphery of a cam disk 129 which is carried by the cam shaft 50. It will be seen that when the cam shaft 50 rotates, the cam 129 will act on the lever 126 to force the link 125 to move rearwardly, thereby swinging the lever 123 and pawl 121 rearwardly. The pawl 121 is accordingly operative to turn the ratchet wheel 120 the distance of one tooth of the ratchet. The cam 110 is so shaped that the extent of rotation imparted to it is sufficient to raise the lever 106 and magazine a distance equal to the spacing of the records R in the magazine. For restoring the pawl 121 to operative position relative to another tooth of the ratchet 120, the cam 129 is provided 60 with a co-operating ledge portion 130 which, with the periphery 129 of the cam, forms a groove 131 which receives the cam roller 128 and serves to positively swing the lever 126 counter-clockwise, as viewed in Figure 3. 75

For disabling the pawl 121 to cause repeating of a record, I have provided a cam device for adjusting the pawl 121 to inoperative position. This device includes a plate member 132 which is mounted on the shaft 111 but not secured thereto. The outer face of the plate 132 engages a friction disk 133 which is carried by a collar 134 secured to the shaft 111. A coil spring 135 compressed between the other face of the plate 132 and the adjacent face of the ratchet wheel 120 serves to maintain the plate 132 in frictional engagement with the friction disk 133. The shaft 111 is provided at its free end with a knob 136 for facilitating manual turning of the shaft. By manually turning the shaft 111 counter-clockwise as viewed in Figure 3, the pawl 121 will be elevated out of engagement with the ratchet by means of a cam edge 137 (see Figures 3 and 7) which acts against a projection 138 formed integral with the ratchet-engaging portion 122 of the pawl. (See Figure 6.) When the projecting portion 138 of the pawl is disposed at the high point 139 of the cam edge 137, the pawl will ride idly over the ratchet teeth. Of course, it will be understood that upon such movement of the pawl, the plate 132 is swung about the axis of the shaft 111. Upon return movement of the pawl, the projection 138 thereof will ride down the inclined cam edge 137 inasmuch as the plate is frictionally held against movement, the frictional holding power being greater than the small amount of friction between the pawl projection 138 and cam edge 137. When the projection 138 engages the leg 140 at the front end 35 of the cam edge 137, it will, of course, positively force the cam plate 132 to move forwardly. As an incident to such movement, the pawl portion 122 will ride upwardly over the back side of one of the ratchet teeth, this being permitted by reason of the depth of the opening over the cam edge 137. As soon as the pawl portion 122 passes over the teeth on its return movement, it will drop down behind the tooth to be in position to engage the same for effecting the necessary adjustment of the record magazine.

A locking pawl 141, pivoted at its lower end as indicated at 142 to a lug formed integral with the base frame 10, is provided for locking the ratchet 120 against rearward rotation. The upper end of the pawl 141 has a laterally extending portion 143 adapted to engage back of each ratchet tooth, a spring 144 serving to yieldably hold the pawl in such position. The lever 123 is provided near its upper end with a projecting lug 145 which is adapted to enter one of the notches 146 formed in the rear edge of the depending post 115. This locking lug 145 serves to prevent adjustment of the record magazine when the parts are in playing position, as illustrated in Figure 4. A pointer 147, secured to one ear 102 of the frame 100, operates with an index chart 148 mounted in fixed position on the supporting framework, this chart being indexed to indicate the selections available in the record magazine. When the phonograph is at rest, i. e., the parts are in non-playing position, and all of the records are in the magazine, the magazine may be adjusted manually to provide for the playing of any selected record. This is accomplished by turning the knob 136 and shaft 111 clockwise, as viewed in Figure 3. The ratchet wheel 120 and the cam 110 are caused to turn under these conditions by means of a ratchet member 149 which is axially, slidably, but non-rotatably mounted on the shaft 111 and adapted to engage a corresponding ratch-

et formation 150 on the cam disk 110. A spring 151 compressed between a lug 152 extending upwardly from the base frame 10 and the adjacent end of the hub of the ratchet 149 serves to yieldingly urge the ratchet 149 into engagement with the ratchet 150. It is important to prevent manual adjustment of the record magazine during such time as a record is disposed on the turntable or in the process of being transferred from the magazine to the turntable, or vice versa. This is accomplished by means of a cam ear 153 struck out of the thrust bar 125 for engaging a flange 154 formed integral with the hub of the clutch 149. When the parts are in playing position, as shown in Figure 4, the cam ear 153 is operative to hold the ratchet member 149 out of engagement with the ratchet 150 so that manual turning of the shaft 111 will be inoperative to adjust the magazine.

The records are transferred from the magazine to the turntable and returned from the turntable to the magazine mainly by means of a pair of co-operating rollers 155 and 156 which extend between opposite frame members 11 and are rotatably mounted therein. The upper roller 155 is mounted in an elongated slot 157 which permits the upper roller to be separated from the lower roller 156. The lower roller 156 is driven by means of a friction wheel 158 which alternately engages the bottom of the turntable 13 and the top of a driving disk 159 which is carried by the spindle 14. The driving wheel 158 is operably connected to the roller 156 by means of a chain 160 which extends around suitable sprockets carried by the shaft of the wheel 158 and the shaft of the roller 156. The record is fed into the bite of the rollers 155 and 156 from the magazine by means of a lever 161 which is pivoted at its lower end, as indicated at 162, on a lug formed integral with the base frame 10. The upper end of the lever 161 is provided with a projection or ear 163 which is designed, upon swinging movement of the lever 161, to engage the adjacent edge portion of a record in the magazine to thereby displace the same towards and into the bite of the said rollers 155 and 156. A record is fed from the turntable 13 to the magazine by means of a lever 164 which is similar to the lever 161 just described. The levers 161 and 164 are connected for simultaneous operation by means of a connecting link or bar 165 which is pivoted, as indicated at 166, to the lever 164, and at 167 to the lever 161. The connecting bar 165 carries an anti-friction roller 168 which co-operates with a segmental cam 169. The connecting bar 165 and the levers 161 and 164 are normally swung to the position indicated in Figure 3 by means of a coil spring 169a which is connected between an upstanding bracket member 170 carried by the bar 165 and a suitably spaced point of the thrust bar 125. Movement under the influence of the spring 169a is limited by means of a stop pin 171 carried by the frame member 12.

As previously stated, the driving wheel 158 is adapted to alternately engage the turntable 13 and the driving disk 159. For controlling engagement of the driving wheel 158, the bracket member 170 of the bar 165 is provided with a pin 172 which co-operates with yielding fingers 173 and 174 which depend from the hub portion 175 of the arm 176 in which the driving wheel 158 is rotatably mounted. The arm 176 is pivoted for rocking movement, as indicated at 177, in a lug depending from the frame 15.

The operation of the mechanism may be briefly

described as follows: Assuming that the mechanism is in the position indicated in Figure 3, i. e., all records are in the record magazine, the record-centering pin 45 and pickup device 23 are elevated and the pick-up device 23 moved to its outermost position, the first operation will be that of displacing a record (in this instance, the record indicated at RX) from its normal position in the magazine into the bite of the rollers 155 and 156. This is accomplished when the roller 168 of the bar 165 is engaged by the front end portion 178 of the cam 169 and the bar 165 is caused to move to the left in Figure 3. The projecting portion 163 of the lever 161 is thus caused to engage the adjacent edge of the record RX to slide the same into the bite of the rollers 155 and 156.

When the bar 165 moved to the left, the pin 172 engaged the yielding member 173 to swing the driving wheel arm 176 upwardly about its pivot to bring the driving wheel 158 into contact with the bottom side of the turntable 13. The turntable is continuously rotated by the electric motor so that rotation of the turntable is transmitted to the wheel 158 and from the wheel 158 by means of the chain 160 to the lower roller 156. The direction of rotation of the turntable is such that the roller 156 is then rotated in a counter-clockwise direction, as viewed in Figure 3, whereby the roller, in co-operation with the upper roller 155, serves to transfer the record to the turntable. The rollers 155 and 156 rotate with sufficient rapidity to impart sufficient momentum to the disk to throw the disk clear of the rollers to a position in which the usual axial opening of the record may be entered by the centering pin 45. Upon completion of the record-transferring operation of the rollers 155 and 156, the roller 168 of the bar 165 drops to the recessed end portion 179 of the cam 169 which permits the spring 169^a to move the bar 165 to the right sufficiently to cause the driving wheel 158 to assume a neutral position, i. e., out of driving engagement with both the turntable and the driving disk 159. At about the same time that the roller 168 engages the recessed cam portion 179, or slightly prior thereto, the cam-engaging end 56 of the lever 53 rides down an inclined portion 180 of the cam 49 and enters the notch indicated at 182, thereby permitting the outer end 57 of the lever 53 to swing downwardly under the weight of the rod 42 and parts supported thereby. When the rod 42 is thus lowered, the centering-pin 45 enters the central aperture of the record and the pick-up device 23 is lowered into engagement with the starting end of the record sound groove. Inasmuch as the fulcrum lever 81 is disposed in its operative position, as shown in Figure 2, lowering movement of the rod 42 will cause the lever 71 to seat on the fulcrum ledge 84, the parts being so arranged that such seating is effected before the rod 42 has reached its lowermost position. During the final portion of the downward movement of the rod 42, the lever 71 is caused to swing about the fulcrum seat 84, with the result that the clutch member 74 is moved upwardly and disengaged from the clutch end of the worm gear 71. The playing of the record is then effected, and when the stylus reaches the innermost groove of the record, the adjusting screw 95 engages the tripping arm 86 to disengage the fulcrum lever 81 from the lever 71 with the result that the cam shaft 50 is again set in rotation. The next succeeding operation to take place is that of elevating the pick-up device and record-centering pin.

This is accomplished through the agency of the cam 49 which operates on the lever 53 in the manner previously explained. After a small amount of turning movement of the cam shaft 50 and the cams carried thereon, the roller 168 of the connecting bar 165 is freed from the recessed cam portion 179 whereby the spring 169^a is permitted to move the bar 165 to the right in Figure 4. The lever 164 is thereby caused to engage the record on the turntable to feed the same into the bite of the transfer rollers 155 and 156. Rotation of the rollers 155 and 156 is then effected in the proper direction to feed the record to the magazine by reason of the fact that in its movement to the right, the pin 112 engaged the yielding member 174 to thereby swing the driving wheel arm 176 downwardly about its pivot to bring the driving wheel 158 into engagement with the driving disk 159. Such engagement between the driving wheel 158 and driving disk 159 is, of course, operative to rotate the wheel 158 in a clockwise direction, the roller 156 being then similarly rotated.

As soon as the record is delivered from the turntable to the magazine, the cam 129 is operative to swing the lever 126 to the right in Figure 4, with the result that the pawl 121 acts on the ratchet wheel 120 to turn the cam 110 a distance sufficient to raise the lever 106 sufficiently with the top of the turntable 13.

If the machine is not provided with coin-control mechanism or the like for stopping its operation upon the completion of one record, the cycle of operation is again repeated. In the event that the machine is provided with coin-control or other means for stopping its operation after the playing of one record, the machine will come to rest with a new record aligned with the turntable, so that the first operation in playing a record will be that of transferring a record from the magazine to the turntable in the manner above described.

The coin-control mechanism indicated at C in Figure 5 may be of any suitable type. In this instance, I have illustrated it as being controlled by means of a short pawl 183 which is designed to be engaged by a pin 184 carried by the cam member 129. It will be seen that each cycle of operation of the mechanism involves one complete revolution of the cam shaft 50, wherefore the pin 184 will engage the coin-control operating lever 183 once for each record played.

The described and illustrated mechanism, as compared with other automatic phonograph mechanisms of similar types, is comparatively simple and free from complicated devices which require a high degree of accuracy in manufacture as well as in the extent of movement imparted to the respective parts. Because of its simplicity, the structure may be manufactured at an unusually low cost and its operation is highly satisfactory and free from the requirement of frequent adjusting.

I am aware that changes may be made in the described structure without departing from the spirit of my invention, the scope of which should be determined by reference to the following claims, the same being construed as broadly as possible consistent with the state of the art.

I claim as my invention:

1. In an automatic phonograph, the combination of a record-storage magazine, a turntable, means for rotating said turntable, means for transferring a record from said magazine to said

- turntable including a pair of rolls adapted to receive the record therebetween, means engaging a portion of the turntable and driven thereby for rotating said rolls, and cam actuated mechanism 5 for effecting engagement and disengagement of said means and turntable in accordance with the record transferring requirements of the phonograph.
2. In an automatic phonograph, the combination of a record-storage magazine, a turntable, means for rotating said turntable, means for transferring a record from said magazine to said turntable including a pair of rolls adapted to receive the record therebetween, a friction wheel 10 engaging a portion of said turntable so as to be thereby driven, means connecting said wheel and one of said rolls for effecting rotation of the latter, and cam actuated mechanism for effecting engagement and disengagement of said means and turntable in accordance with the record transferring requirements of the phonograph.
3. In an automatic phonograph, the combination of a record-storage magazine, a turntable, means for rotating the turntable, means for alternately transferring records from said magazine to said turntable and from said turntable to said magazine, means for effecting such alternate operation of said record-transferring means, including a driving disk connected to said turntable in vertically spaced relation thereto, a rotary member interposed between said turntable and driving disk, and means for alternately effecting engagement of said rotary member with said turntable and driving disk.
4. In an automatic phonograph, the combination of a record magazine, a turntable, means for rotating said turntable, roller means interposed between said turntable and record magazine for transferring a record from the magazine to the turntable, a rotary member adapted to engage said turntable and connected to said roller means for actuating the latter, means for initially advancing the record from said magazine to said roller means, and means actuated by said initial record-shifting means for effecting engagement of said rotary member with said turntable.
5. In an automatic phonograph, the combination of a record magazine, a turntable, means for rotating said turntable, roller means interposed between said turntable and magazine for transferring a record from the magazine to the turntable and from the turntable to the magazine, a driving disk spaced vertically from the turntable and connected thereto for rotation in unison therewith, a rotary member adapted to alternately engage said turntable and driving disk, said rotary member being connected to said roller means for actuating the latter, means for initially shifting the record from said magazine or turntable to said roller means, and means actuated by said initial record-shifting means for effecting alternate engagement of said rotary member with said turntable and driving disk.
6. In an automatic phonograph of the class described, the combination of a record-storage magazine, a turntable, means for rotating the turntable, a pair of rolls interposed between said turntable and said magazine for shifting a record from the magazine to the turntable and from the turntable to the magazine, a driving disk fixedly connected in vertically spaced relation to said turntable, a rotary member interposed between the turntable and driving disk, means for effecting alternate engagement of said rotary member with said turntable and driving disk to thereby effect rotation of the former successively in opposite directions, means connecting said rotary member with one of said rolls for rotating the latter, record-displacing means respectively associated with oppositely disposed portions of said magazine and turntable respectively, a rotary cam, means connecting said record-displacing means and having operative engagement with said cam whereby the latter is effective to simultaneously actuate said record-displacing means, and means carried by said cam-actuated means for alternately effecting engagement of said rotary member with said turntable and said driving disk to thereby effect rotation of said record-transferring rolls alternately in opposite directions.
7. In an automatic phonograph, the combination of a record magazine, a turntable, said magazine being adapted to support a record with its lowermost surface substantially in horizontal alignment with the top surface of said turntable, means for transferring a record from said magazine to said turntable and from said turntable to said magazine comprising a pair of vertically disposed levers respectively located at oppositely disposed portions of said record magazine and said turntable, each of said levers being pivotally mounted at its lower end for swinging movement about a horizontal axis and each of said levers having a finger at its upper end for engaging an adjacent edge portion of a record, a bar connecting said levers, a rotary cam, and means carried by said bar for engaging said cam whereby the latter is operative to effect pivotal movement of said levers.
8. In an automatic phonograph, the combination of a record magazine, a turntable, said magazine being adapted to support a record with its lowermost surface substantially in horizontal alignment with the top surface of said turntable, means for transferring a record from said magazine to said turntable and from said turntable to said magazine comprising a pair of vertically disposed levers respectively located at oppositely disposed portions of said record magazine and said turntable, each of said levers being pivotally mounted at its lower end for swinging movement about a horizontal axis and each of said levers having a finger at its upper end for engaging an adjacent edge portion of a record, a bar connecting said levers, a cam for shifting said bar and levers in one direction, and spring means for shifting said bar and levers in the opposite direction.
9. In an automatic phonograph, the combination of a record magazine, a turntable, said magazine being adapted to support a record with its lowermost surface substantially in horizontal alignment with the top surface of said turntable, means for transferring a record from said magazine to said turntable and from said turntable to said magazine comprising a pair of rolls disposed intermediate said magazine and said turntable, a pair of vertically disposed levers respectively located at oppositely disposed portions of said record magazine and said turntable, each of said levers being pivotally mounted at its lower end for swinging movement about a horizontal axis and each of said levers having a finger at its upper end for engaging an adjacent edge portion of a record, a bar connecting said levers, a rotary cam, means carried by said bar for engaging said cam whereby the latter is operative to effect pivotal movement of said levers, said levers being thereby respectively operative

to feed a record from the magazine and turntable into the bite of said rolls, means for alternately effecting rotation of said rolls in opposite directions, and means controlled by said bar for controlling rotation of said rolls.

ment of the bar is operative to control the position of said wheel, said connection including resilient means for yieldingly maintaining said wheel in said selective driving engagement.

12. In an automatic phonograph, a record magazine for supporting a plurality of records in substantially horizontal position, means for mounting said magazine for vertical adjustment, a cam for effecting vertical adjustment of said magazine, means for effecting step-by-step rotation of said cam including a ratchet wheel connected to said cam, a pawl having one end engaging the teeth of said ratchet wheel, a cam-actuated reciprocating member having the other end of said pawl connected thereto, means selectively operable for disengaging said pawl from said ratchet wheel to prevent shifting of said magazine, comprising an adjustable cam device adapted in one position of adjustment to elevate said pawl out of operative engagement with said ratchet wheel, means whereby said cam device is caused to move in unison with said pawl when the latter is moved idly in ratchet-turning direction, and friction means for resisting movement of said cam device for maintaining said cam stationary relative to the pawl during return movement of the latter to operative relation with said ratchet wheel.

13. In an automatic phonograph, a record magazine for supporting a plurality of records in substantially horizontal position, means for mounting said magazine for vertical adjustment, a cam for effecting vertical adjustment of said magazine, means for effecting step-by-step rotation of said cam, comprising a ratchet wheel connected to said cam, a pawl having one end engaging the teeth of said ratchet wheel, a cam-actuated reciprocating member having the other end of said pawl connected thereto, means selectively operable for disengaging said pawl from said ratchet wheel to prevent shifting of said magazine, comprising a cam plate mounted for pivotal adjustment about the axis of said ratchet wheel, said cam plate having a cam edge, means projecting from said pawl and engaging said cam edge, means for adjusting said cam plate to elevate said pawl out of operative engagement with the ratchet wheel, means whereby said pawl effects movement of said cam plate in unison with the pawl when the latter is moved idly over the ratchet teeth in ratchet-turning direction, means resisting adjustment of said cam plate whereby said pawl rides idly over said cam edge upon its return movement into operative relation with said ratchet teeth.

11. In an automatic phonograph, the combination of a record magazine, a turntable, said magazine being adapted to support a record with its lowermost surface substantially in horizontal alignment with the top surface of said turntable, means for transferring a record from said magazine to said turntable and from said turntable to said magazine comprising a pair of rolls disposed intermediate said magazine and said turntable, a pair of vertically disposed levers respectively located at oppositely disposed portions of said record magazine and said turntable, each of said levers being pivotally mounted at its lower end for swinging movement about a horizontal axis and each of said levers having a finger at its upper end for engaging an adjacent end portion of a record, a bar connecting said levers, a rotary cam, means carried by said bar for engaging said cam whereby the latter is operative to effect pivotal movement of said levers, said levers being thereby respectively operative to feed a record from the magazine and turntable into the bite of said rolls, means for alternately effecting rotation of said rolls in opposite directions, said last-mentioned means including a driving disk fixedly connected to said turntable in vertically spaced relation thereto, a wheel disposed intermediate said turntable and driving disk, means for mounting said wheel in such position for vertical adjustment selectively into engagement with either said turntable or driving disk, a driving connection between said wheel and one of said rolls, and a connection between said bar and said wheel-mounting means whereby shifting move-

14. In an automatic phonograph, the combination of a turntable, a pick-up device including an arm pivotally mounted at one end for both horizontal and vertical swinging movement and provided at its other end with a stylus holder, a rod mounted for vertical sliding movement, a spider secured to the upper end of said rod and having a portion adapted to engage a portion of said pick-up, means for effecting upward sliding movement of said rod thereby to elevate said pick-up from the record upon completion of the playing of the latter, and means for swinging said pick-up from its inner finishing position to its outer starting position comprising a member actuated by said rod during its upward movement, and a rigid but adjustable connection between said member and the pick-up arm.

15. In an automatic phonograph, the combination of a record magazine, a turntable, means for transferring a record from said magazine to

said turntable, means for delivering the record to be transferred to said transferring means comprising a vertically disposed lever pivotally mounted at its lower end and provided at its upper end with a finger for engaging a record in said magazine, a cam, and a member pivoted at one end to said lever and having mounted thereon cam engaging means, said cam being thereby operative to rock said lever to cause said finger to engage and move a record from its normal position in the magazine to said transferring means.

16. In an automatic phonograph, the combination of a record magazine, a turntable, means for transferring records from said magazine to said turntable, a spindle supporting said turntable, means for rotating the spindle and turntable, a pick-up device including an arm mounted for both horizontal and vertical movement relative to the turntable, means including a vertically movable rod operative in its upward movement to effect movement of said pick-up device outwardly upon completion of the playing of a record and operative in its downward movement to lower said pick-up into record playing position, a rotary shaft for operating said record transferring means, intermeshing gears on said spindle and shaft respectively, a clutch device on said spindle for disengageably connecting the spindle gear to the spindle for controlling operation of said rotary shaft, a lever pivotally mounted at one end on said vertically movable rod and having at its other end a connection with said clutch device, a shiftable member having a portion engaging said lever for supporting the same in position to hold said clutch device disengaged, and means connected with said pick-up arm for effecting shifting of said member to release said lever to thereby cause said clutch device to be engaged for driving said rotary shaft, said lever being so arranged relative to said shiftable member that when said rod and the end portion of a lever pivoted thereto are lowered, the lever will engage said member and rock thereon so as to disengage said clutch device.

17. In an automatic phonograph, the combination of a turntable, a pick-up device including an arm pivotally mounted at one end for both horizontal and vertical swinging movement and

provided at its other end with a stylus holder, a rod mounted for vertical sliding movement, a spider secured to the upper end of said rod and having a portion adapted to engage a portion of said pick-up, means for effecting upward sliding movement of said rod thereby to elevate said pick-up from the record upon completion of the playing of the latter, and means for swinging said pick-up from its inner finishing position to its outer starting position comprising a member actuated by said rod during its upward movement, and a connection between said member and the pick-up arm.

18. In an automatic phonograph, means for effecting step by step movement of a record magazine, said means comprising a ratchet wheel, a pawl having one end engaging the teeth of said ratchet wheel, means for reciprocating said pawl for actuating said ratchet wheel, a movable cam member operatively connected to said pawl and manually adjustable to a position for maintaining said pawl in inoperative relation to said ratchet wheel so as to cause the pawl to move idly over the teeth of said ratchet wheel, and interengaging means on said movable cam member and pawl for restoring said cam member to normal position permitting operative engagement of said pawl and ratchet wheel as an incident to said idle movement of said pawl.

19. In an automatic phonograph, a pick-up normally moved in one direction during the reproduction of a record, means for elevating said pick-up to a position free of the record upon completion of the playing thereof, said means comprising a vertically movable member, a clutch for controlling the operation of said vertically movable member, a clutch control lever operatively connected to said clutch and to said vertically movable member, a movable fulcrum adapted to engage a portion of said lever during its movement with said vertically movable member so as to cause continued movement thereof to effect rocking of said lever, thereby to effect disengagement of said clutch, and means actuated by said pick-up upon completion of the playing of a record for moving said fulcrum out of engagement with said lever to permit the clutch to be engaged.

EMIL C. MUELLER.
